UNITED STATES PATENT OFFICE.

JABEA F. SHAWHAN, OF DAYTON, OHIO, ASSIGNOR OF ONE-HALF TO JAMES W. CARPENTER, OF SAME PLACE.

ARC LAMP.

SPECIFICATION forming part of Letters Patent No. 417,516, dated December 17, 1889.

Application filed March 23, 1888. Serial No. 268,267. (No model.)

To all whom it may concern:

Be it known that I, JABEA F. SHAWHAN, a citizen of the United States, residing at Dayton, in the county of Montgomery and State 5 of Ohio, have invented certain new and useful Improvements in Electric Lamps, of which the following is a specification.

My invention relates to electric-arc lamps, and more especially to that class of arc lamps 10 known as "focusing-lamps," wherein the arc is maintained at one specific point; and the object of my invention is to produce a lamp which is simple and compact in construction, positive and regular in operation, and that is 15 not liable to get out of order when subjected to jars or disturbances, so that the lamp is adapted, among other things, for use as locomotive or other head-lights; and the invention consists in the combinations and arrangements of devices, substantially as hereinafter 20 more particularly pointed out, whereby I am enabled to attain such objects.

Referring to the accompanying drawings for a better description of my invention, Figure 1 is a top plan view of a lamp embodying my invention. Fig. 2 is a partial side view, partly in section. Figs. 3 and 4 are respectively plan and side views of a detail. Figs. 5 and 6 are respectively plan and side views 25 of a motor which is adapted to operate with my lamp. Fig. 7 is a diagrammatic representation of the circuits of said lamp. Fig. 8 is a plan view of another lamp embodying the essential principles of my invention. Fig. 9 is a vertical section thereof. Fig. 10 is a section 30 of the negative electrode, and Fig. 11 is a side view showing one way of using my lamp in connection with the reflector of an ordinary head-light.

In constructing a focusing-lamp I have 40 found it desirable to make use of a non-consuming negative electrode, which is fixed in any desired manner with relation to the lamp and to the movable electrode, and in the 45 drawings, as in Fig. 2, I have shown the negative electrode 1 as supported upon a bracket 2, secured to the case or frame 3, which supports or incloses the operative mechanism of the lamp. The movable or positive electrode 50 4 is secured in a moving carrier 5, which may

be of any desired construction, and, as it is desirable to positively feed this upper electrode, I provide means whereby this may be done, and I have shown the carrier as sliding upon guide-rods 6, fixed to the case or frame 55 of the lamp, and the carrier is also provided with an internal-screw-threaded opening, through which the screw-rod 7 passes and in which it turns to raise or lower the carrier on the rod 6. I have found it desirable to make 60 the carrier, or so much thereof as forms the internal screw-thread, of rawhide, as this material furnishes a strong thread for the screw-shaft and requires no lubricant. In this way, it will be seen, that I am enabled to move the 65 upper or positive electrode with absolute accuracy and to maintain it in any position without danger of disturbing its position by shocks or jars or other disturbances which are especially incident to the use of such a 70 lamp on a locomotive.

In order to feed or move the positive electrode for the purpose of establishing or maintaining the arc, it is only necessary to rotate the screw-shaft 7 in the proper direction and 75 the electrode will be moved regularly, evenly, and positively, as required. This screw-rod 7 may be moved by many different devices; but I have shown one I have found to be very efficient, and in which the electro-magnet 8, 80 the coils of which are included in the main-line circuit passing through the arc, is located on the frame in any convenient position, and in suitable relation thereto is placed another electro-magnet 9, the coils of which are included in a high-resistance shunt-circuit 85 around the arc. These magnets are provided with extended pole-pieces 10 and 11, respectively, which in this instance are shown as extending toward each other, which will operate upon armatures 12, which are mounted upon and carried by a frame 13, which is loosely mounted on the extension of the screw-shaft 7. This frame is free to move on its axis 90 when no current is on the lamp, and secured to 95 and moving with the frame is a segment-piece 14, located above the gear-wheel 15, which is fixed upon the extension of the screw-shaft 7; also secured upon said extension is a rocking bar 16, one end of which carries a double 100

pawl 17, which is wide enough to cover the teeth in the gear-wheel 15 and to normally bear upon the periphery of the segment 14, as shown in Fig. 4, and to the other end of this bar 16 is attached a link 18, connected to a wrist-pin 19, eccentrically mounted upon the gear-wheel 20, which is continuously operated by some suitable power. It will thus be seen that the bar 16 is constantly vibrated by the moving power, and when the lamp is in its normal position the segment 14 prevents the pawl from impinging upon the teeth of the gear 15 to operate it; but as soon as the frame 13 is moved in either direction by the magnets operating on the armature 12, connected thereto, the segment 14 will be moved to one side or the other as the case may be, so that the pawl 17 will impinge upon one of the teeth of the wheel 15 and rotate the screw-shaft 7 in the desired direction and raise or lower the upper carbon. Of course the direction of motion imparted to the shaft 7 will depend upon the condition of the arc between the electrodes—as, for instance, when the lamp is started the electrodes are supposed to be in contact, and the current flowing through the arc, as shown in Fig. 7, passes through the coils of magnet 8 and energizes the same, so that the pole-pieces 10 exert their influence upon the armatures 12 so as to move the frame 13 toward the left, and thus, carrying the segment 14 with it, allows the pawl 17 to move the wheel 15 in a direction to raise the holder 5 to establish the arc. As the arc is established and the resistance thereof increases, a portion of the current is diverted through the high-resistance magnet 9, and the pole-pieces 11 exert an influence on the armature and tend to restore the frame 13 to its normal position, and as long as the resistance of the arc is normal the frame will be so held that the segment 14 will prevent the pawl 17 from operating upon the gear-wheel 15 in either direction, and the upper electrode is held stationary and rigid, and is not liable to disturbances from shocks or jars; but as soon as the resistance of the arc increases, so that the effect of the current flowing through the shunt-magnet 9 overbalances the effect of the current flowing through main magnet 8, the frame 13 will swing to the right and the pawl 17 will operate upon the gear 15 to move the screw-shaft 7 in a direction to feed the electrodes toward each other.

It will thus be seen that at all times the electrodes are held and maintained steadily in their proper positions, and that the feed to establish or maintain the arc is positive, and at the same time exceedingly sensitive, so that a slight variation in the normal resistance of the arc will be felt in the magnets, and the mechanism operated to immediately and positively adjust the electrodes to compensate for the disturbance.

In Figs. 8 and 9 I have illustrated a modi-

fied arrangement which embodies substantially the same principles, but in which the screw-shaft 7 is located at one side of the main frame 3 of the lamp mechanism. ordinary lamp, while the lower or negative electrode is fitted into the burner 43 of the oil-lamp and suitably connected in the circuit, so that at all times the ordinary oil-lamp 5 is in position to be lighted.

I have shown one construction of lamp in which 60 is the wick of the Argand burner; 61, the spider-frame having openings 36 for the passage of the air; 30, the negative-electrode carrier, which is expanded so as to act as the usual flame-spreader or button of the burner; and 62 is the burner-cap, of thin metal, which serves to hold the glass chimney in place when used.

15 By simply removing the chimney and the cap 62 and inserting the upper electrode 4 the lamp may be changed so as to use electricity, the negative electrode and oil-burner remaining in position in the focus of the reflector.

20 As before stated, I may make use of any suitable motor for operating the driving-gear 20; but I have found an electric motor such as I am about to describe of special advantage for use in this connection, in that it requires very little current to propel it and it is regular and comparatively slow in its movements. This motor consists, essentially, of the field-magnets 40, having polar projections 41, between which rotates an armature composed, essentially, of two non-magnetic disks

35 42, as of copper, upon which are mounted a series of magnetic bars 43, five being shown in the present instance; and attached to the shaft of the armature is a commutator 44, consisting of a disk 45 of conducting material, having a number of portions 46 of insulating material corresponding to the number of magnetic bars 43. This motor is shown in the diagram constituting Fig. 7 as included 40 in a shunt around the lamp; and the field-magnets are wound with parallel wires in the manner indicated, so that the current entering, for instance, at the plus pole passes through the coils 47 to the conductor 48 and by 45 the brush 49 through the disk 45 to the brush 50, and thence by the wire 51 through the coils 52 to the point 53, and thence through the coils 54 to the minus pole. It will thus be seen that under these conditions the upper 50 magnet 40 is energized while the lower magnet is neutral, the current passing through the parallel coils thereof in opposite directions. As soon, however, as the commutator rotates, so that the brush 49 bears upon an 55 insulated portion thereof, the current from the plus pole will pass through the coils 47 to the point 56, and thence through the coils 56 in the opposite direction, and by the conductor 51 to the brush 50, thence through the 60 commutator-plate 45 to the brush 57, and through the coils 54 to the minus pole, the coils 52 of this latter magnet being out of circuit, and the lower magnet 40 is therefore energized and operates in turn upon the 65 armature.

While I have thus described and illus-

trated one embodiment of my invention, it will be understood that I am not limited to the precise construction and arrangement shown and described, as it is evident these 70 may be varied in many ways, and that parts of my invention may be used together with the others, or separately in combination with other equivalent devices.

What I claim is—

75 1. The combination, with a casing inclosing the operative parts of the mechanism, of a fixed electrode, a carrier supporting a movable electrode, guide- rods mounted on the casing and passing through said carrier, a propelling-screw operating said carrier, a constantly-operated motor inclosed in the casing, a vibrating bar carrying a pawl for driving said screw, and electro-magnets also inclosed in the casing for controlling the operation of 85 said pawl, substantially as described.

2. In an electric-arc lamp, the combination, with a movable electrode, of a motor for propelling the same, electro-magnets controlling the operation of the motor, and gear-connections between the motor and the shaft, the said gear-connections being located in a separate compartment of the case or frame, whereby they may be lubricated without affecting the electrical apparatus, substantially as de- 95 scribed.

3. In an electric lamp, a non-consuming negative electrode consisting of a shell of copper having a small perforation at its closed end, and a carbon inclosed in the case, substantially as described.

4. In an electric-arc lamp, a non-consuming negative electrode consisting of a shell of copper having a small perforation at its closed end, a block of carbon inclosed in said case, 105 and a spring-support for maintaining the carbon in position, substantially as described.

5. In a head-light, the combination, with an electric lamp having a movable positive electrode and an ordinary oil-lamp, a separate 110 negative electrode mounted on the burner of the oil-lamp, substantially as described.

6. The combination, in a head-light, of a reflector, an electric lamp having a movable positive electrode fastened through the upper 115 orifice of the reflector, an ordinary oil-lamp, and a separate negative electrode mounted in the burner of the oil-lamp, substantially as described.

7. In a head-light, the combination of the 120 reflector, an electric lamp mounted upon a standard supporting the reflector and having a moving positive electrode passing through the upper orifice of the reflector, a motor for moving said electrode positively to establish 125 and maintain the arc, an ordinary oil-lamp, and a fixed non-consuming electrode supported in the burner of the oil-lamp, substantially as described.

8. In an electric-arc lamp, the combination, 130 with a movable electrode and a screw-shaft for propelling the same, of an electric motor

arranged in a shunt around the lamp, a constantly-vibrated arm operated by the motor, a pawl carried by the arm, an electro-magnet in the main circuit of the lamp controlling the operation of the pawl to establish the arc, and another electro-magnet in a shunt around the lamp controlling the operation of the pawl to regulate the arc, substantially as described.

In testimony whereof I have signed my name to this specification in the presence of 10 two subscribing witnesses.
